Primary Examiner — Catherine A Tuttle(74) *Attorney, Agent, or Firm* — Mallory M. Henninger; Advent, LLP(57) **CLAIM**

The ornamental design for a dispenser system, as shown and described.

DESCRIPTION

FIG. 1 is a top plan view showing our new design for a dispenser system;

FIG. 2 is a bottom plan view thereof;

FIG. 3 is an exploded front elevation view thereof;

FIG. 4 is an exploded rear elevation view thereof;

FIG. 5 is an exploded left side elevation view thereof;

FIG. 6 is an exploded right side elevation view thereof;

FIG. 7 is an exploded top, front, and left isometric view thereof;

FIG. 8 is an exploded top, rear, and right isometric view thereof; and,

FIG. 9 is an exploded top, front, and left isometric view thereof.

The broken lines depict portions of the dispenser that form no part of the claimed design. The appearance within the unshaded interior regions visible in FIGS. 4, 8, and 9 likewise form no part of the claimed design.
